UNITED STATES PATENT OFFICE.

CYRUS H. LATHAM, OF LOWELL, MASSACHUSETTS, ASSIGNOR TO HIMSELF,
EDWARD P. WOODS, AND DANIEL SHERWOOD, OF SAME PLACE.

IMPROVEMENT IN CAKE AND FRUIT-BASKETS.

Specification forming part of Letters Patent No. 118,027, dated August 15, 1871.

To all whom it may concern:

Be it known that I, CYRUS H. LATHAM, of Lowell, in the county of Middlesex and State of Massachusetts, have invented a new and Improved Basket for Domestic use for Holding Fruit, &c., of which the following is a specification:

My invention consists in a novel manner of making a basket of wire; and it has for its object a cheap, strong, and highly-ornamental article for domestic use, which can be readily taken apart and "nested" or closely packed for transportation.

Figure 1 is a perspective view of my improved basket. Fig. 2 is a sectional view through the center of the nut and screw which unite the base and top together. Fig. 3 is a view illustrating the manner of bending the ribs of the basket. Fig. 4 is a perspective view representing a holder of different shape secured to the base in place of the basket part A.

The basket A is constructed of wire ribs or strands *a*, bent to the desired shape, and arranged around a common center at regular distances, with their outer ends *b* bent over to grasp and support the ring *d* which forms the rim of the basket. The inner ends of the wires *a* are securely held in position in the screw *D*; which is cast to them, as plainly shown in the drawing. The base B I form of wire upon a machine patented to me April 18, 1871, No. 113,779, to which reference is hereby made. This base when taken from the machine is in the form of a wire cylinder or blank, which is afterward brought to the prop-

er shape between dies or upon a former. The two parts, base and basket, after they are bent into shape, are treated to a bath of tin in a molten state, or plated with any substance, to prevent their corroding and to beautify their appearance. The ends of the wires *c* have a nut, *C*, cast to them in a similar manner as the wires which form the basket, and this nut is screw-threaded to receive the screw *D*, by which the two parts are secured together. The metal of which the nut and screw *C* *D* are composed is of the same color and general appearance as the coated or plated wire forming the other parts of the basket.

By this method of construction baskets and holders of various shapes may be used with a single base, as is represented in Fig. 4 of the drawing, and I intend so to make and sell them with baskets adapted to hold fruits, flowers, cake, &c.

When the metal for the nut and screw *C* and *D* is one that requires a higher degree of heat to fuse than the temperature of the molten tin of the bath the parts can be coated with the tin after the nuts and screws are cast to them instead of before, as above described.

I claim as my invention—

The basket A and base B, made of wire and united together, substantially as described and for the purposes specified.

CYRUS H. LATHAM.
